UNITED STATES PATENT OFFICE.

WALTER HILL, OF EASTON, MASSACHUSETTS.

CARTRIDGE-LOADING MACHINE.

SPECIFICATION forming part of Letters Patent No. 351,981, dated November 2, 1886.

Application filed June 4, 1886. Serial No. 204,138. (No model.)

To all whom it may concern:

Be it known that I, WALTER HILL, of Easton, county of Bristol and State of Massachusetts, have invented an Improvement in 5 Cartridge-Loading Machines, of which the following description, in connection with the accompanying drawings, is a specification, like letters on the drawings representing like parts.

This invention is an improvement upon Letters Patent of the United States granted to me December 22, 1885, and has for its object to so construct the machine that it may be more easily and rapidly operated and be more efficient in loading cartridges with various grades 15 of material.

In accordance with this invention the powder and shot chambers are provided with exits by which the chambers may be emptied at any time to be refilled with material of another grade. A wad-receptacle is provided, from which the wads pass to a chute, from which they are taken one at a time by a perforated slide and conveyed over the general-delivery chute of the machine, a plunger operated by a lever being employed to force the wads through the general-delivery chute. Means are also provided under the control of a hand-lever for automatically moving the slide which conveys the wads from the wad-chute to the general-delivery chute back and forth. The valves controlling the passage of ammunition from each chamber are arranged 25 to be operated from one side of the machine. A suitable locking device is employed for locking the cartridge-shell in fixed position at the orifice of the general-delivery chute, the mechanism being so arranged as to allow the shell to be brought into suitable position to be acted 30 upon by a crimper.

Figure 1 shows in side elevation a cartridge-loading machine embodying this invention; Fig. 2, a sectional detail showing a portion of the wad-chute and wad-carrying slide and a cartridge-shell in position to be filled; Fig. 3, a vertical section of Fig. 1, taken on the dotted line $x-x$; Fig. 4, a detail of a portion of the machine, showing the wad-receptacle partially broken out; Fig. 5, a top view of the locking device for locking the cartridge-shell 45 in position beneath the general-delivery chute, and also the crimper; and Fig. 6, a detail to be referred to.

The chambers a , b , to receive powder and shot, and the valves g , g' , controlling the passage from said chambers to the general-delivery chute e , are all substantially as in the patent referred to. In this instance the valves g , g' are retained normally in elevated position by spiral springs g'' .

The chambers or compartments a , b , together with their attached parts, are rigidly connected to an upright frame, A , by arms A' , A'' , said frame being attached to the bed-plate B , adapted to be applied to any suitable table, B' , by a clamping-screw, B'' , turning in a suitable bracket, B''' . A receptacle, c , having an inclined bottom, c' , and an inclined guide portion, c'' , at the foot of the inclined bottom c' , is mounted upon and preferably pivoted to the top of the chamber a by a screw, c^3 , the said receptacle c serving also as a lid to cover the opening a' at the top of the chamber a . The guide portion c'' of the receptacle c conveys wads placed in the said receptacle into the wad-chute c^4 , (see Figs. 2 and 4,) extending vertically in front of the machine, between the two chambers a , b , said wad-chute having a slit or opening, c^5 , extending vertically its entire length, through which a suitable tool may be passed to aid the downward movement of the wads should they become lodged. A lid, b' , is hinged to the top portion of the chamber b , covering the opening b^2 therein.

At the lower portion of the chambers a , b suitable exits, a^3 , b^3 , are provided, which are closed by any suitable screw-cap, a^4 , b^4 , in order that the contents of either chamber may be withdrawn when desired to change the grade of material being used, or for any other purpose.

The valves controlling the passage of material from the chambers a , b to the general-delivery chute e are operated by rods g^3 , g^4 , the rod g^3 having a thumb-piece, g^5 , attached to its lower end by which the said rod may be drawn downward, returning, as will be noticed, by the force of the spring g^2 , while the rod g^4 is connected with a hand-lever, g^6 , pivoted to one side of the frame A , its opposite end being bent substantially at right angles, in order that it may be operated from the same side of the machine as the rod g^3 . The distance the valves g , g' shall be moved is ad-

justed, as in the patent referred to, by suitable adjusting-screws, g^1 , and blocks g^3 . A suitable ring, e^1 , is secured within the end of the general-delivery chute e , and a detachable 5 ring, e^2 , of suitable internal diameter to fit the external diameter of the cartridge being filled is placed within the orifice or lower end of the said general-delivery chute, the said ring e^2 being held in position by a pivoted locking- 10 lever, c^1 .

The plunger consists of a tube, n , through which is passed the rod n' , encircled by a spiral spring, n^2 , (see Fig. 3,) bearing against a cap, n^3 , fitted into the upper end of the tube 15 n , and also against a pin, n^4 , passing through the tube near its lower end, the pin bearing against a projection or flange, n^5 , and moving as the plunger is depressed in guideways or slots n^6 at each side of the tube n . The plunger 20 is operated by a lever, L , pivoted at L' to a standard, L^2 , supported by the frame-work A , said lever L passing through an eye, L^3 , having a shank portion, n^7 , (see Fig. 3,) which is fitted into the top of the tube n , 25 and connected therewith and also to the rod n' by a pin, 20, (see Fig. 3,) so that the plunger n may be operated, when desired, by the said lever. The wads are taken one at a time from the wad-chute by a wad-carrying 30 slide, m , having a hole or perforation at m^1 , which receives the lowermost wad from the wad-chute c^4 and conveys it into the general-delivery chute e , in order that the plunger n may force the same from the slide m into and 35 through the ring e^2 , forming part of the general-delivery chute and into the cartridge-shell p .

The wad-carrying slide m is actuated by the lever m^4 , pivoted at m^5 , the upper end of the 40 said lever having a hooked end, m^6 , (see Fig. 6,) which engages and follows upon a guideway, m^7 , secured to the top of the lever L , a spring, m^8 , connected with the lever m^4 , moving the hooked end of the said lever m^4 upon 45 the guideway m^7 when the lever L is depressed. The lever L is normally retained in elevated position by the spring n^2 within the plunger n . A suitable loop, L^4 , is attached at one end to the standard L^2 , the said loop serving as a 50 rest or support for the usual box (not shown) containing wads, one end of the said box being opened to allow the wads to pass therefrom into the wad-receptacle.

As the lever L is depressed the wad-carrying slide m is moved in the direction of the arrow, Fig. 2, taking a wad from the wad-chute c^4 , and conveying the same into the line of the general-delivery chute, the hooked end piece, m^6 , following forward upon the guide 55 portion m^7 , and as the lever L is restored to its normal position, the guide m^7 , gradually inclining, causes the said rod m^4 to be returned to its normal position, moving the wad carrying slide in the opposite direction.

60 The cartridge-shell p is placed within a barrel, p' , supported by a ring, p^1 , pivoted at p^2 (see Figs. 3 and 5) to a cross-bar, p^3 , turning

freely within two side bars of a shell-carrying frame, p^5 p^6 , pivoted to the frame-work A at p^7 . A suitable locking device, consisting of a 70 bar having two engaging ends, p^8 p^9 , and pivoted at its center, as at p^{10} , is employed to be turned beneath the sides p^3 of the said shell-carrying frame, and raise it sufficiently to place the cartridge-shell p , when upturned in vertical 75 position, correctly next to and so as to enter the ring e^2 , to receive the charge or box filled. When the locking device is released, the side pieces, p^4 , will rest upon the bed-plate B , and then the cartridge-shell p may be turned or 80 tipped over at right angles, as shown at Fig. 5, or parallel with the bed-plate, as shown in dotted lines, Fig. 1, to bear upon a suitable support, S , carried by a sliding frame, S' , having a suitable upright, S^2 , in which the crimper S^3 85 has its bearings, the said slide-frame carrying the crimper being moved by a suitable hand-lever, S^4 , all as in the patent referred to. It will thus be seen that by depressing the thumb-piece g^5 a suitable supply of powder, for instance, may pass through the general-delivery chute and enter the shell p . Then the lever L may be operated, as described, to convey a wad into suitable position to be driven by the plunger into the shell, after which the hand-lever g^6 may be operated to allow a suitable 90 supply of shot to pass through the general-delivery chute and enter the shell and the lever L be again operated to drive a wad. The locking device p^8 p^9 is then released and the cartridge-shell brought at right angles upon the 95 sliding crimper-frame and crimped in the usual manner.

By locating the thumb-piece g^5 and the operating end of the lever g^6 , both on one side of the machine, they may be operated with one hand and the operating-lever L be moved by the other hand.

As it is frequently desired to load a few cartridges with one grade of ammunition and then 100 to employ another grade, the exits a^3 b^3 will be frequently used.

The ring e^2 may be detached and another 105 ring of another internal diameter supplied when desired.

It is obvious that any other suitable locking device may be employed, instead of the device herein shown, for elevating the frame carrying the cartridge-shell.

The wad-receptacle is locked in position by 110 a suitable locking device, herein shown as a pivoted latch, o .

I claim—

1. In a cartridge-loading machine, two ammunition compartments, a general-delivery chute with which they are in communication, and valves controlling the passages to said chute, combined with the thumb-piece g^5 , and the lever g^6 , arranged below the said valves and adapted to be operated from the same side of the machine, the rods g^3 and g^4 , for connecting said thumb-piece and lever with said valves, and the retracting-springs g^2 , substantially as set forth.

2. In a cartridge-loading machine, two ammunition compartments, a general delivery chute with which they are in communication, and valves controlling the passage to said chute, combined with a wad-receptacle having an inclined-guide portion, c^2 , and wad-chute, into which the wads pass from the wad receptacle, substantially as described. 40
3. In a cartridge-loading machine, the combination, with two ammunition compartments, of a general delivery chute with which said compartments communicate, and valves controlling the passage between said compartments and chute, said compartments being provided at their bottoms with delivery apertures or exits, as $a^3 b^3$, whereby they may be emptied, when desired, without using the said valves, substantially as set forth. 45
4. In a cartridge-loading machine, two ammunition compartments, a general delivery chute communicating therewith, and valves controlling the passages between said chute and compartments, combined with a wad-chute, a wad-carrying slide, a plunger, a lever for operating said plunger, and a second lever receiving movement from the plunger-operating lever and adapted to actuate the said wad-carrying slide, substantially as set forth. 50
5. In a cartridge-loading machine, two ammunition compartments, a general delivery chute communicating therewith, and valves controlling the passages between said chute and compartments, combined with a wad-chute, a wad-carrying slide below said chute, the plunger-operating lever L, having the 55
- guideway m^7 , the standard to which said lever is pivoted, and the lever m^4 , engaging the said wad-carrying slide and having the hooked end m^6 , adapted to said guideway, substantially as set forth. 60
6. The horizontally-pivoted shell-holder p^2 , arranged to be turned down or tipped over, as described, and the pivoted frame to which said shell-holder is attached, combined with a locking device, as the pivoted bar having engaging ends $p^8 p^9$, for holding said frame in an elevated position, substantially as set forth. 65
7. In a cartridge-loading machine, the ammunition chambers or compartments, general-delivery chute, valves, and plunger, combined with a wad-receptacle pivoted at the top of one of the ammunition chambers and covering the opening therein, and a locking device for locking the said wad-receptacle in position to permit the wads to pass therefrom into the 70 wad-chute, substantially as described.
8. In a cartridge-loading machine, the ammunition-chambers, general-delivery chute, valves, and plunger, combined with a wad-chute, wad-receptacle having an inclined bottom, and a wad-rest, L^1 , in which the box containing the wads may be placed, all substantially as described. 75

In testimony whereof I have signed my name to this specification in the presence of two subscribing witnesses.

WALTER HILL.
